UNITED STATES PATENT OFFICE

JOHN WILLIS MOORE, OF JACKSONVILLE, FLORIDA

DESIGN FOR A BOTTLE

Application filed September 6, 1932. Serial No. 44,759. Term of patent 14 years.

To all whom it may concern:

Be it known that I, JOHN WILLIS MOORE, a citizen of the United States, residing at Jacksonville, in the county of Duval, and State of Florida, have invented a new, original, and ornamental Design for a Bottle, of which the following is a specification, reference being had to the accompanying drawing forming part thereof.

Fig. 2 is a view in front elevation thereof.

I claim:—

The ornamental design for a bottle, as shown.

JOHN WILLIS MOORE.
